UNITED STATES PATENT OFFICE.

HENRY CULL, OF CHICAGO, ILLINOIS.

MARBLE-HANDLING MACHINE.

Application filed October 28, 1921. Serial No. 511,083.

To all whom it may concern:

Be it known that I, HENRY CULL, a citizen of the United States, and a resident of the city of Chicago, in the county of Cook 5 and State of Illinois, have invented certain new and useful Improvements in a Marble-Handling Machine; and I do hereby declare that the following is a full, clear, and exact description of the same, reference being had 10 to the accompanying drawings, and to the numerals of reference marked thereon, which form a part of this specification.

Stone cutters, when working on large blocks of marble or other bodies of heavy 15 material, often experience considerable trouble in manipulating a block of marble to conveniently position the different surfaces to be worked on.

This invention therefore relates to an im- 20 proved type of a marble handling machine wherein a block of marble is adapted to be supported in slings from a circumferentially grooved cylinder or drum which may be manually rotated by gear mechanisms 25 and a hand wheel to cause movement of the slings over the drum, thereby rotating the block of marble into any desired position of adjustment to facilitate working thereon.

It is an object of this invention to provide 30 a machine whereby blocks of stone may be conveniently turned to permit a stone cutter to have access to the different surfaces or parts of a block of stone.

It is also an object of the invention to pro- 35 vide a stone handling machine wherein a large block of stone may be suspended and conveniently turned by operating a hand wheel.

Another object of the invention is to pro- 40 vide a marble handling machine wherein a yoke suspended from a crane or other support has a grooved drum journaled therein for supporting a block of marble by means of endless slings, said drum adapted to be 45 rotated by operating a hand wheel and gears so that the slings will act to rotate the block of marble into different positions so that the same may be cut or carved.

It is an important object of this invention 50 to provide a marble handling machine of simple and effective construction adapted to permit a block of marble to be suspended in endless rope slings from a grooved drum which, when rotated, will cause tipping of 55 the block of marble into different positions

so that the same may be conveniently worked on by a stone cutter or carver.

Other and further important objects of this invention will be apparent from the disclosures in the specification and the 60 drawings.

The invention (in a preferred form) is il- 65 lustrated in the drawings and hereinafter more fully described.

On the drawings:

Figure 1 is a front elevation of a marble handling machine embodying the principles of this invention and shown supporting a block of marble.

Figure 2 is an end view thereof showing 70 the operation of the slings and block in dotted lines.

Figure 3 is an enlarged detail section taken on line 3—3 of Figure 1.

Figure 4 is a detail sectional end view of 75 the drum taken on line 4—4 of Figure 3.

Figure 5 is a fragmentary view taken on line 5—5 of Figure 1.

Figure 6 is an enlarged end view taken on line 6—6 of Figure 1 with parts broken 80 away.

Figure 7 is a view taken on line 7—7 of Figure 1.

Figure 8 is a front elevation of a modi- 85 fied form of a marble handling machine with the slings omitted.

Figure 9 is an end view thereof.

Figure 10 is a top plan view taken on line 10—10 of Figure 8.

Figure 11 is a sectional view taken on 90 line 11—11 of Figure 8.

Figure 12 is a sectional view taken on line 12—12 of Fig. 8.

Figure 13 is a detail side view of the lower 95 portion of the shaft bearing.

Figure 14 is an enlarged detail section taken on line 14—14 of Figure 8.

As shown on the drawings:

The reference numeral 1 indicates a hook supported at one end of a hoisting chain 2. 100 The chain 2 is carried by a crane, windlass or other suitable support (not illustrated).

The marble handling device comprises a yoke or frame embracing a beam 3 sup- 105 ported at the middle by a pair of bars 4. The bars 4 are bolted to the beam 3 and have the upper portions thereof deflected inwardly toward one another and connected by means of a bolt 5, around which the sup- 110 porting hook 1 is engaged. Inverted U-

- shaped straps or brackets 6 and 7 are hung over the ends of the beam 3 and are rigidly held in place by bolts 8 or other suitable means.
- 5 Supported between the arms of the bracket 6 is a bearing 9 secured in place by a bolt 10. A double bearing 11 is supported between the arms of the bracket 7 and is held in place by a bolt 12. Rotatably supported by the bearings 9 and 11 is a shaft 13. Secured on one end of the shaft 13 adjacent the outer end of the bearing 9 is a retaining collar 14. Keyed or otherwise secured on the other end of the shaft 13 adjacent the bearing 11 is a large gear 15 which is in mesh with a small gear or pinion 16 keyed on a stub shaft 17 supported in the lower portion of the double bearing 11. Keyed on the outer end of the stub shaft 17 adjacent the pinion 16 is a hand wheel 18. Pivotedly mounted on one end of the beam 3 above the bearing 11 is a double pawl 19 having teeth 20 and 21 integrally formed thereon for coaction with the gear 15.
- 25 Mounted on the shaft 13 between the bearings 9 and 11 is a drum comprising a wooden cylinder 22 provided with a plurality of spaced peripheral V-shaped grooves 23. The ends of the cylinder 22 are beveled as at 24. Rigidly secured to each end of the cylinder 22 by screw bolts 25 is a metal end member 26 provided with a bevel surface 27 adapted to coact with the beveled surface 24 to afford a V-shaped groove. The drum end members 26 are keyed to the shaft 13.
- Removably engaged in two of the drum grooves 23 are a pair of endless rope slings 28 adapted to support a block of marble 29.
- 40 Figures 8 to 14 inclusive illustrate a modified form of a marble handling machine comprising a lower bearing member or casting 30 cut away on both sides to form recesses at 31 and having integrally formed on each side thereof a projection 32 and a side wall 33. The upper portion of the lower bearing member 30 is provided with a concave groove wherein a strong steel main shaft 34 is seated. The shaft 34 is held in place by a grooved upper bearing member 35 which is bolted to the lower bearing member 30. Both end portions of the shaft 34 are longitudinally grooved to receive keys 36. A collar 37 is secured on the shaft 34 adjacent one end of the bearing 30-35 by means of a set screw 38. Secured on the shaft 34 adjacent the other end of the shaft bearing 30-35 is a large gear 39 held in place by a set screw 40. Slidably engaged on each end of the shaft 34 and its key 36 is a pulley wheel 41 having a V-shaped peripheral groove 42. Each pulley wheel 41 is adapted to have engaged thereon an endless rope sling similar to the slings 28 shown in Figures 1 and 2.

Both ends of a U-shaped strap or yoke 43 are engaged in the recesses 31 and against the projections 32 of the lower bearing member 30 and are secured in place by bolts 44 or other suitable means. Disposed longitudinally within the yoke 43 is an auxiliary or driving shaft 45 the inner end of which is journaled in an opening in the lower bearing member 30. The outer end of the driving shaft 45 projects through the bight of the yoke 43 and has a chain pulley wheel 46 secured on the projecting end thereof. Secured on the driving shaft 45 adjacent the inner side of the yoke bight is a collar 47 held in place by a set screw 48. Secured on the driving shaft 45 adjacent the lower bearing member 30 is a pinion 49 which is in mesh with the large gear 39. Rigidly secured on each side of the lower bearing member on the wall 33 thereof, by bolts 50, is a supporting strap or bar 51, the ends of which are deflected. The upper ends of the bars 51 are connected by a bolt 52 to receive the hook 53 which is attached to the end of a hoisting chain (not shown). The lower ends of the bars 51 are connected by a bolt 54 on which a hook 55 is engaged. Trained around the pulley wheel 46 is a chain 56 adapted to be pulled to cause rotation of the pulley wheel 46 and the driving shaft 45.

The operation is as follows:

When it is desired to cut or carve a block of marble the handling machine is lowered by means of the chain 2 which may be unwound from a windlass or lowered by other suitable means. The two slings 28 are then engaged around the block of marble 29 and set in two of the drum grooves 23, as illustrated in Figure 1, the grooves selected depending upon the length of the block 29. The chain 2 is now elevated to raise the marble block to a convenient height to permit a stone cutter to work thereon. As the block 29 is lifted off of the ground the slings 28 are tensioned and seat tightly in the drum grooves.

When it is desired to turn the marble block 29 from the full line position in Figure 2 into the dotted line position A, the hand wheel 18 is turned to the right thereby causing rotation of the pinion 16 which in turn acts to rotate the large gear 15 and the drum toward the left looking at Figure 2. The pawl 19 is thrown outwardly with the tooth 21 clicking over the gear teeth. When the block 29 reaches position A and rotation of the hand wheel is stopped, the pawl 19 is manually thrown into the dotted line position of Figure 7 and falls by gravity with the tooth 20 thereof engaging between two of the teeth of the gear 15, thereby locking said gear and the drum against further rotation toward the left. The marble block is tipped by means of the

rope slings 28 which seat tightly in the drum grooves and are rotated with the drum.

If the marble block is moved from the dotted line position B of Figure 2 into the 5 position A, the hand wheel 18 is manually turned toward the left looking at Figure 2, thereby causing the gear 15 and the grooved drum to be rotated in a clockwise direction. To hold the marble block 29 in position A, 10 the pawl 19 is positioned in the dotted line position of Figure 7 and holds the gear 15 and the drum locked against a reverse rotation.

It will thus be seen that the large marble 15 block 29 may be moved into different positions by merely rotating the hand wheel 18. The gear ratio between the small gear or pinion 16 and the large gear 15 is such that one person may easily cause rotation of the 20 block 29 into different positions to permit work to be conveniently done on all sides of said block.

In the modified form of the marble handling device illustrated in Figures 8 to 14 25 inclusive, the device is hung on the hook 53 attached to the chain or cable of a hoisting machine. An endless sling is engaged on each of the pulley wheels 41. A block of marble is engaged in the slings and the device is elevated by the hoisting machine chain to raise the block of marble to a convenient height to permit a stone cutter to work thereon. As the block of marble is 30 lifted from the ground the slings are tensioned and seat tightly in the grooves 42 of the pulley wheels 41. The two pulley wheels 41 are adjustable longitudinally on the main shaft 34 to permit blocks of marble of different sizes to be handled by the machine.

40 When it is desired to turn the block of marble the chain pulley wheel 46 is turned by pulling on the chain 56, thereby causing rotation of the driving shaft 45 and the pinion 49 mounted thereon. The pinion acts to 45 rotate the large gear 39 and the main shaft 34 on which the grooved pulley wheels 41 are adjustably secured. The pulley wheels 41 are thus rotated thereby causing the slings to be rotated to turn the block of marble 50 carried thereby. The pull chain 56 is provided to permit turning of a block of marble when in an elevated position wherein it would be impossible for a person working on the block of marble to reach a hand wheel 55 without lowering the entire device.

In case it is desired to use the hoisting machine for elevating other articles or de-

vices, the lower hook 55 may be used instead of the upper hoisting machine hook 53 thereby making it unnecessary to remove the 60 marble handling device from said hook 53.

I am aware that numerous details of construction may be varied through a wide range without departing from the principles of this invention, and I therefore do not 65 propose limiting the patent granted otherwise than necessitated by the prior art.

I claim as my invention:

1. A marble handling machine comprising a frame, a shaft journalled therein, a grooved 70 drum secured on said shaft to rotate therewith, endless slings engaged on said drum to support a marble block, a large gear on said shaft, a pinion in mesh therewith, a hand wheel connected to rotate said pinion 75 to cause rotation of said gear and drum whereby the slings act to rotate said marble block, and means on said frame adapted to engage said gear to hold the same locked against a reverse rotation in either direction. 80

2. An article handling machine comprising a frame having depending ends, a drum between said ends and rotatably supported thereby, a plurality of endless rope slings 85 encircling said drum, said drum having a plurality of V-shaped grooves therearound for the reception of and frictional engagement with said slings, the number of grooves being in excess of the number of slings to enable the position of the slings to be varied 90 to suit the length of the article to be handled, and means for rotating said drum.

3. An article handling machine comprising a frame having depending ends, a drum between said ends and rotatably supported 95 thereby, an endless rope sling encircling said drum, said drum having a V-shaped groove therearound for a frictional engagement with said sling, and means for rotating said drum.

4. A block handling device comprising a frame, a drum rotatably supported thereon having a plurality of V-shaped peripheral 105 grooves therein, endless rope slings engaged in said grooves adapted to carry a block, and means for rotating said drum to cause said slings to rotate the block.

In testimony whereof I have hereunto subscribed my name in the presence of two subscribing witnesses.

HENRY CULL.
